US0D1004086S

(12) **United States Design Patent** (10) Patent No.: **US D1,004,086 S**
(45) Date of Patent: ** Nov. 7, 2023

(54) **SPINAL IMPLANT INSERTER**

(71) Applicant: **WARSAW ORTHOPEDIC INC.**,
Warsaw, IN (US)

(72) Inventors: **Anthony J. Melkent**, Germantown, TN
(US); **Thomas E. Drochner**,
Longmont, CO (US); **James P. Duncan**, Hernando, MS (US)

(73) Assignee: **Warsaw Orthopedic, Inc.**, Warsaw, IN
(US)

(**) Term: **15 Years**

(21) Appl. No.: **29/732,069**

(22) Filed: **Apr. 21, 2020**
